R. DE ARAZOZA,
MEANS FOR RAISING SUNKEN VESSELS,
APPLICATION FILED SEPT. 27, 1917.

Patented July 30, 1918.

2 SHEETS—SHEET 2.

UNITED STATES PATENT OFFICE.

RAFAEL DE ARAZOZA, OF HABANA, CUBA.

MEANS FOR RAISING SUNKEN VESSELS.

1,274,230.

Specification of Letters Patent. Patented July 30, 1918.

Application filed September 27, 1917. Serial No. 193,516.

To all whom it may concern:

Be it known that I, RAFAEL DE ARAZOZA, a citizen of the Republic of Cuba, residing at Habana, Cuba, have invented new and useful Improvements in Means for Raising Sunken Vessels, of which the following is a specification.

It has heretofore been proposed to raise sunken ships by means of an apparatus adapted to generate gases and by compressed air for driving the water out of the compartments of the vessel. However, the presence of the air confined within the interior of the apparatus has been the cause of the formation of an air cushion within the compartments tending, especially at great depths, to destroy the usefulness of the apparatus on account of the enormous pressure which is apt to flatten or even crack the hull of the same.

The present invention is intended to avoid these disadvantages by providing an apparatus in which the gases of any kind are generated within the inner vessel and also allows the manufacture of the apparatus chiefly of very thin plates.

According to the present invention, the charge of substances generating the gas can be divided in such a manner that a diver by operating one of two operating triggers, can develop such a quantity of gas as is necessary to allow a convenient handling of the device for attaching the apparatus to the vessel to be raised in which movement the cable to which the floating vessel is secured on board the salvage vessel can be detached and the diver can change the position of the body to be raised in such a manner that it may take up a position most convenient for this raising by attaching the apparatus to one or the other side of such body.

The apparatus according to the present invention is of very simple construction and does away with a number of unnecessary parts adapted to complicate the apparatus and to reduce its power of traction.

A further object of the invention is to be seen in the use of a liquid seal, as oil or another substitute between the water contained in the outer body of the apparatus and the generated gases in the inner body in order to prevent a dissolution of the latter in the water due to the great pressure which they must have in order to counteract the exterior pressure of the water upon the ap-

paratus while the same is descending and which is increasing at the rate of 0.1 kg. for each square cm. for each meter of depth.

In the accompanying drawing:

Figure 1 is a longitudinal section through the apparatus.

Fig. 2 is a similar section through said apparatus taken on a rectangle to the view shown in Fig. 1 and showing the interior of the inner vessel.

The outer vessel A of the apparatus has the form of a truncated cone made of iron plates with a convex bottom and top, or any other form, in the center of which a body or vessel B of smaller dimensions of the same shape and material is embodied which projects more or less at both ends above or below the vessel A. The interior of said vessel B constitutes a chamber in which the chemical substances for the generation of the gases are deposited. The vessel B also has a convex bottom and top G.G and is provided at its lower extremity with a reinforcing collar to which are secured the eyes for attaching the chains or cables for securing the apparatus to a vessel to be raised. C is a tube which is passed through the body A and permits the passage of a rod D which connects a handle L with the rod I of one of the triggers for releasing the chains. Cables R and R' are secured to the rod D and the end of the rod I of one of the triggers, respectively, and are adapted to be operated by the diver, and from the surface. Said cables attached to the rods D and I are guided over rollers E.E. At the top of the vessel B an opening F is provided through which the chemicals are supplied to the vessel B and which is conveniently closed. F' is an opening at the bottom of said vessel B for the removal of dirt and sediment collecting within said vessel and for cleaning the same. Stuffing boxes H.H are provided at the points of entrance of the rods I.I in the vessel B and around said rods coil springs I'.I' are wound tending to hold the rods I.I in position. J is a partition in the center of the vessel B which divides the central part of the vessel into two equal chambers which are equally high and in which the charge of chemical substances is to be divided according to the wish of the operator. Any suitable number of partitions, chambers or bottom plates may be provided. Plates K.K swinging around a common pivot X are

adapted to close the bottom of the chambers formed by the partition J.

A ball M of sufficient water displacement to counterbalance the weight of the chain 5 or wire cable, or any other fastening means, and the hooks attached thereto is intended to be conveniently handled by the diver for positioning the apparatus. Chains N N are secured to one end of each of said bottom plates K K, while their other ends are secured to the top of the vessel B.

A valve O is provided as shown, and is adapted to let the air confined within the vessel A escape and, at the same time, serves 15 as means for the introduction of oil into the vessel A.

Plugs P P are provided at the top of the two T-pieces secured to the top of the vessel A and the sides of the vessel B and are 20 screwed into two inner valves Q Q. These valves are intended to prevent the entrance of water from the outer vessel into the inner one and for permitting the passage of the gases generated within the inner vessel 25 toward the exterior.

S is a hand wheel upon the upper end of a rod which is guided through a guide plate W and which permits the convenient opening and closing of the bottom valve T to 30 any desired degree. This valve is spring controlled and permits the inundation of the outer vessel and the expulsion of the water contained therein according to the selection of the strength of said springs, 35 while the other valve is automatically working.

The apparatus operates in the following manner: The cover F of the inner vessel B is lifted and a quantity of water is supplied 40 through the opening which is sufficient for generating a volume of gas from the chemical charge within said vessel (if acetylene gas is used 56.25% water is necessary) in order to decompose the calcium carbid; and 45 in case of other gases being generated or used, a quantity of chemical substances is introduced through said top opening in the proper proportions. Hereafter, the chains N N are pulled until the bottom plates K K 50 are completely in horizontal position at which moment the links of said chains will be caught by one of the rods I I of the corresponding trigger device which has been pushed in position by the corresponding 55 spring I'. In this manner the charge will be equally divided into two parts or portions by means of the partition J. The upper opening F is now closed again and through the valve O a sufficient volume of 60 oil or another substance is introduced to form a mantle or seal of about 4 to 5 mm. thickness upon the water which enters the vessel A and in this manner the escape of the gases into the water which afterward shall 65 be expelled is prevented and the loss of

a great volume of the gas generated is avoided. The apparatus is now in condition for submersion.

The hand wheel S is now operated to make several turns in order to open the valve T 70 and to permit the entrance of water into the vessel A. The valve O is then opened for allowing the air contained within the vessel A to escape in the same proportion in which it is replaced by the water entering 75 through the valve T until all of the air has been expelled and the vessel A is now completely inundated and without air confined in its interior, in order to prevent deformation which necessarily would produce an increasing pressure.

After the vessel A has been completely submerged, the valve O and the valve T will be closed, the latter by a respective turn of the hand wheel S and the vessel which is 80 now in condition for submersion is held by a cable passed through the eyes provided for this purpose upon its upper cover. In this condition the apparatus will descend by its own weight until its reaches the application 85 point. In this state the diver entrusted with the work of raising a vessel can conveniently manipulate the apparatus by means of the ball and chain and secure the same to the vessel to be raised, and by getting a hold 90 on the handle L can operate the rod connected therewith which will cause the fall of one part of the charge supported by the corresponding bottom plate K to be precipitated upon the bottom of the interior of the 100 vessel B and a volume of gas will be developed which will expel half of the water (more or less) contained in the vessel A so that the apparatus which is firmly anchored, 105 will exert a pull upon its point of anchorage which permits the hauling in of the cable to which it is fastened without danger that the apparatus leave its place. The other trigger is operated from the surface with a cable R' at the starting moment of the raising 110 operation and is secured to a buoy which approximately indicates at the surface of the water the location of the apparatus. By the operation of the cable R' the rest of the charge will be precipitated so that the 115 maximum traction force of the floating vessel will be produced.

It will be clear that if a sufficient number of floating devices is used, that the united force of all will be sufficient to overcome the 120 dead weight of the submerged body, the displacement of which is known so that it can be raised to the surface. It will therefore only be necessary to draw the respective chains or cables in order to bring the vessel 125 to be raised into the proper position.

In Fig. 2 one of the chains connected to a plate K is shown after having been operated by the diver.

In the same measure in which the ascent 130

is progressing the exterior pressure will be progressively lessened while the inner pressure would remain constant if no regulating valves are provided, so that the destruction 5 of the apparatus would be caused. This, however, is avoided by the automatic operation of the valves T T which are provided for equilibrating the pressure at all times in such a manner that when the apparatus 10 reaches the surface of the water, in its interior, a pressure only will prevail which is equal to the atmospheric pressure and to the resistance to which the tension of the springs has been selected which tend to close 15 said valves. The tension of the springs has been previously selected in such a manner that the interior pressure is slightly higher than the outside pressure on account of the resistance of said springs. During the time 20 of the ascent, the excess of gas which is not used for the proper operation of the apparatus has escaped through the valves T T.

If the apparatus is to be stored away it is only necessary to open the bottom at the 25 point F' in order to remove the dirt and sediment and to clean the apparatus and let it dry.

Having thus described my invention, what I claim is:

30 1. In a device of the character described, a vessel, a gas generator in said vessel, a means for dividing said generator into two charge chambers, means turning around a common pivot and constituting the mov- 35 able bottom for said chambers, and chains secured to one end of each of said means constituting said bottom and with their other ends to the top of said vessel for alternately operating one or the other bottom of said 40 chambers for allowing one or the other part of the charge to be deposited into the bottom of the generator, trigger devices near the top of the vessel, extending through the sides thereof for operating said chains to ac- 45 tuate said bottom constituting means, and a seal between the water contained in the vessel and the gas generated within the generator, substantially as described.

2. In a device of the character described, 50 a vessel, a cylindrical gas generator concentrically arranged within said vessel, a par-

tition wall centrally disposed within said generator for dividing the same into two chambers, a movable bottom plate for each of said chambers pivotally secured to a common center and adapted to support the charge, chains secured to one end of each of said bottom plates and with their other ends to the top of said vessel for alternately releasing one or the other of said plates for 60 dropping the charge contained in one or the other of said chambers into the generator, trigger devices near the top of the vessel extending through the side walls thereof operating said chains, and means for regulating the air and water supply and exhaust, 65 substantially as described.

3. In a device of the character described, a vessel, a cylindrical gas generator concentrically arranged within said vessel, a partition wall centrally disposed within said generator for dividing the same into two chambers, a movable bottom plate for each of said chambers pivotally secured to a common center and supporting the 70 charge, chains secured to one end of each of said bottom plates, trigger devices for operating said chains, manually operated means for operating said trigger devices, and spring controlled bottom valves in said 75 vessel for automatically regulating the supply of water, and means for exhaust of the air and gas, substantially as described.

4. In a device of the character described, 80 a vessel, a gas generator arranged within said vessel, means for dividing the generator into a plurality of chambers, a movable bottom plate for each of said chambers pivotally secured to a common center and supporting the charge, chains secured with one 85 end to the bottom and the other to the top of the generator, and a plurality of T-pieces secured to and connecting both vessels, valves attached inside of said T-pieces, and plugs entering said T-pieces for controlling 90 said valves for avoiding air pockets and allowing the entrance of water into the generator, and a ball float for counterbalancing 95 the weight of the attaching means for allowing a ready handling of the apparatus.

RAFAEL DE ARAZOZA.
